CUFF LINK

Joseph Carlton Bagnall, Attleboro, Mass., assignor, by mesne assignments, to Swank Products, Inc., Attleboro, Mass., a corporation of Delaware

Application July 16, 1935, Serial No. 31,607

9 Claims. (Cl. 24—102)

This invention relates to a cuff link; and has for one of its objects the provision of a cuff link having a body and heads at its ends with at least one of the heads movable so that it may be easily inserted through the buttonholes of a cuff and then moved to prevent retraction of the link from the cuff.

Another object of the invention is the provision of a cuff link, the heads of which may be provided with ornaments upon its ends to enhance the appearance thereof.

Another object of the invention is the provision of a cuff link which will be simple to manufacture and yet one which when positioned in the cuff will be attractive in appearance.

Another object of the invention is the provision of a construction which may have a variety of forms or different appearances and yet a construction having basically and fundamentally the same operating parts for the mechanical action thereof.

With these and other objects in view, the invention consists of certain novel features of construction, as will be more fully described, and particularly pointed out in the appended claims.

In the accompanying drawing:

Fig. 1 is a perspective view of the cuff link with its heads in retaining position;

Fig. 2 is a perspective view showing one of the heads swung through 90° that it may be more easily inserted through the buttonholes of a cuff;

Fig. 3 is a perspective view showing the movable head detached;

Fig. 4 is a perspective view of the movable head;

Fig. 5 is a perspective view of the body portion of the link with the arms in spread apart position prior to the assembly of the parts;

Fig. 6 is a perspective view of the fixed head;

Fig. 7 is a sectional view taken on line 7—7 of Figure 2;

Fig. 8 is a sectional view on line 8—8 of Figure 6;

Fig. 9 is an end view of the structure shown in Figure 1;

Fig. 10 is a perspective view of a modified form of body;

Fig. 11 is a side elevation showing the form of body illustrated in Figure 10 made up into a link;

Fig. 12 is a sectional view through the structure shown in Figure 11 and showing the mounting of the fixed head in position on the end of the body.

55 In separably securing two parts of a garment

together, such for instance as cuffs about the wrist of the wearer, it is desirable to have one of the heads which abut the outer surface of the cuff movable to a position to offer a minimum of resistance to its insertion through the buttonholes, and then subsequently movable to a position of greater resistance to prevent withdrawal; and in order to accomplish this result in a very simple way and yet in a structure which may be ornamented that it may have an attractive appearance when positioned in the cuff, I have provided a structure which may be assembled without a soldering operation by simply shaping the parts into a desired configuration, whereby they will be retained with resilience although without the necessity of providing a coiled spring or the like for this purpose; and the following is a more detailed description of the present embodiment of this invention, illustrating the preferred means by which these advantageous results may be accomplished:

With reference to the drawing, I have provided a body designated generally 10. One form which this body may have is that of a strip of stock bent up into the desired shape, as shown in Figure 5, shaped at its fold to embrace a fixed head designated generally 11 and provide spaced arms 12 for pivotally receiving a movable head 14 between them, these parts being shown in Figures 4, 5 and 6 in perspective.

The fixed head 11 consists of a tubular shell 15 which is generally square in cross section, there being a core 16 of a solid rod positioned within this tube and stopping short of the ends thereof to provide seats 17 for the reception of the base 18 of a gem 19 against them, while the edges 20 of the tube about this seat are rolled inwardly over the tapering base portion of the gem 19 to securely hold the gem in position at either end of this head. Centrally of the head a recess is provided in the rod 16 and the stock of the tube is forced into this recess as at 22 to retain the tube on the rod and itself provide a recess 23 to assist in centering this head in the body.

The body part as shown in Figure 5 consists of a single strip of stock which is bent into a shape and size to embrace the fixed head shown in Figures 6 and 8, at its central portion. This is accomplished by bending the stock, as at 26, at spaced points along the portion 27 and then again as at 28 that the stock may extend inwardly from opposite sides toward the center or axial line of the body where it is again bent as at 29 to extend along for a short distance with the portions 30, 31 in contact with each other.

The portion 27 of the stock fits in the recess 23 so as to center the fixed head and prevent it from movement laterally with reference to the center line of the body, there being a snug fit of this embracing portion of the body and the fixed head so that the parts are securely held in position.

The portions 30, 30 of the body after they extend for a short distance in contact with each other branch outwardly by reason of the bends 31 and 32 to provide the arms 12, which extend from the bends 32 in substantially parallel relation. Adjacent the ends of the arms bearing openings 33 are provided while on the inner surface of each arm projections or ribs 34 and 35 are formed in crucifix form at right angles to each other. The bearing openings 33 being located at the crossing point of these ribs, as clearly shown in Figure 5.

20 The head 14 consists of an outer shell 36 and an inner rod or solid member 37 stopping short of the end for the reception of a gem 38 at either end thereof. This rod is held in position by means of a pin 39 extending through the tube 36 and rod and projecting from either side to provide trunnions 40, as shown in Figure 4. There is also provided recesses 41 and 42 in the tube 36 or head 14 at right angles to each other with their points of crossing at the axis of the trunnions 40. These grooves or recesses 41 and 42 being of a size to snugly receive the projections 34 and 35 on the arms 12 and maintain this head in different positions.

25 The stock of the head 14 is bulged outwardly or 30 is arcuate in shape, as at 43 so as to lie flush with the ends of the arms 12 as at 44, see Figure 1, so that no sharp edges will occur when the device is in working position.

30 For assembly, it is merely necessary to position 40 the fixed head 11 with its recess engaging the bar 27 and to position the head 14 with its trunnions 40 in the bearing openings 33 and then draw the arms 12 toward each other to cause the stock at one end of the body to tightly embrace 45 the fixed head 11 and at the same time draw the arms 12 into close contact with the movable head 14 and to then secure the contiguous parts of the body 30, 30 in such position by placing a rivet 45 through portions of the arm 30 so that the 50 movable head cannot be dislodged and the arms will be in such position as to cause the protuberances 34 and 35 to enter the recesses 41 and 42 in the movable head 14. The arms 12 are sufficiently resilient from the point of the rivet 45 to 55 their ends 44 so that when pressure is applied to turn or rotate the movable head 14, these arms will spread apart slightly permitting dislodgement of the rib and grooves and movement about the pin 40 as an axis. As a right angular position 60 is reached the projections will again snap into the recesses in the head to hold the head in a position as shown in Figure 2, returning to the position shown in Figure 1 upon further or reverse rotation.

65 In some cases instead of causing the body to embrace the fixed head, I may provide separate arms, such as shown at 46 in Figure 10 and provide a head consisting of a cup-like structure 47 with an opening 48 therein for the reception of 70 an offset portion 49 of the body arms 46, the cup being recessed as at 50 to receive these offset fingers 49 on the arms 46.

The arms are separately threaded through the opening 48 to position the fingers 49, as shown 75 in Figure 12, and at the same time the head

such as 14 is positioned between the arms of the body 46 and a rivet 51 secures these arms in position to hold the movable head assembled and also hold the fixed head in a riveted position at the end of the body. 5

A suitable gem 52 may be set upon the cupped head 47 with its edges 53 turned over the tapering edges of the stone or gem 52 to hold the same securely thereto. In this manner I may provide a more or less conventional form of head on a 10 structure having the desired action as above pointed out in further detail. 10

The foregoing description is directed solely 15 towards the construction illustrated, but I desire it to be understood that I reserve the privilege of resorting to all the mechanical changes to which the device is susceptible, the invention being defined and limited only by the terms of the appended claims. 15

I claim:

20 1. In a cuff link, a body having a resilient bifurcated portion at one end, a pin extending across between the arms of said bifurcated portion, a head pivotally mounted on said pin as an axis and of a size to swing between said bifurcated portion, a head at the other end of the body, and interlocking means partly on said head and partly on said bifurcated portion to hold the head in different selected positions. 25

2. In a cuff link, a body having a resilient 30 bifurcated portion at one end, a pin extending across between the arms of said bifurcated portion, a head pivotally mounted on said pin as an axis and of a size to swing between said bifurcated portion and a head at the other end of the body, 35 and interlocking means between said head and bifurcated portion to hold the head in different selected positions, said means consisting of projections on one part and recesses on the other part to receive said projections, the resilience of said arms 40 functioning to hold said interlocking means in different selected positions.

3. In a cuff link, a body having a resilient 45 bifurcated portion at one end, a pin extending across between the arms of said bifurcated portion, a head pivotally mounted on said pin as an axis and of a size to swing between said bifurcated portion and a head at the other end of the body, and interlocking means between said head and bifurcated portion to hold the head in different selected 50 positions, consisting of a projection on one part and crucifix recesses on the other part to receive said projections, the resilience of said arms functioning to hold said interlocking means in different selected positions. 55

4. In a cuff link, an elongated head, a body formed of a length of material embracing said head with portions extending in contiguous relation for a distance therefrom and then branching out into spaced arms, and a second elongated 60 head pivotally mounted between said arms.

5. In a cuff link, an elongated head, a body formed of a length of material embracing said head with portions extending in contiguous relation for a distance therefrom and then branching out into spaced arms, a second elongated head pivotally mounted between said arms, and means holding said contiguous portions in close relation to secure both of said heads in mounted position. 65

6. In a cuff link, an elongated head, a body 70 formed of a length of material embracing said head with portions extending in contiguous relation for a distance therefrom and then branching out into spaced arms provided with bearing openings at their ends, a second elongated head 75

having trunnions pivotally mounted in said openings for pivoting said head in said arms, means holding the contiguous portions of said body against spreading whereby said arms are held in desired spaced relation to hold the movable head mounted and said body is held tightly about said first head to hold it in position.

5. In a cuff link, an elongated head, a body formed of a length of material embracing said head with portions extending in contiguous relation for a distance therefrom and then branching out into spaced arms provided with bearing openings at their ends, a second elongated head having trunnions pivotally mounted in said openings for pivoting said head in said arms, and a single rivet holding the contiguous portions of said body against spreading whereby said arms are held in desired spaced relation to hold the movable head mounted and said body is held 10 tightly about said first head to hold it in position.
6. In a cuff link, a pair of arms with their ends in spaced relation and then offset into contiguous relation inwardly from the ends, an elongated head pivotally mounted between said spaced portions of said arms and contacting said arms for movement from a position in line with the arms to a position at right angles to the arms, a rivet for holding the contiguous portions of said arms in contact and the arms in contact with said head, and interengaging means on the contacting surfaces of said arms and head to hold said head in different definite positions of adjustment with relation to said arms.
7. In a cuff link, an elongated head, a body formed of a length of material embracing said head with portions extending in contiguous relation for a distance therefrom and then branching out into spaced arms provided with bearing openings at their ends, a second elongated head having trunnions pivotally mounted in said openings for pivoting said head in said arms, and a single rivet holding the contiguous portions of said body against spreading whereby said arms are held in desired spaced relation to hold the movable head mounted and said body is held 15 tightly about said first head to hold it in position.
8. In a cuff link, a pair of arms with their ends in spaced relation and then offset into contiguous relation inwardly from the ends, an elongated head pivotally mounted between said spaced portions of said arms and contacting said arms for movement from a position in line with the arms to a position at right angles to the arms, a rivet for holding the contiguous portions of said arms in contact and the arms in contact with said head, and interengaging means on the contacting surfaces of said arms and head cooperat- 20 ing with the resiliency of said arms to hold said head in different definite positions of adjustment with relation to said arms.

tions of said arms and contacting said arms for movement from a position in line with the arms to a position at right angles to the arms, a rivet for holding the contiguous portions of said arms in contact and the arms in contact with said head, and interengaging means on the contacting surfaces of said arms and head to hold said head in different definite positions of adjustment with relation to said arms.

9. In a cuff link, a pair of resilient arms with their ends in spaced relation and then offset into contiguous relation inwardly from the ends, an elongated head pivotally mounted between said spaced portions of said arms and contacting said arms for movement from a position in line with the arms to a position at right angles to the arms, a rivet for holding the contiguous portions of said arms in contact and the arms in contact with said head, and interengaging means on the contacting surfaces of said arms and head cooperat- 15 ing with the resiliency of said arms to hold said head in different definite positions of adjustment with relation to said arms.

JOSEPH CARLTON BAGNALL.
